PLANTER LAMP

Edward E. Mecus, Shorewood, Wis., assignor to Dexter-Mahnke Inc., Milwaukee, Wis., a corporation of Wisconsin

Application February 9, 1953, Serial No. 23,497

Term of patent 3½ years

(Cl. D48—20)

To all whom it may concern:

Be it known that I, Edward E. Mecus, a citizen of the United States, and a resident of Shore-wood, Wisconsin, have invented a new, original,
and ornamental Design for a Planter Lamp, of which the following is a specification, reference being had to the accompanying drawing forming a part hereof.

Fig. 1 is a front elevational view of a planter lamp showing my new design; and

Fig. 2 is a side elevational view.

I claim:

The ornamental design for a planter lamp, as shown.

EDWARD E. MECUS.
